REFRIGERATING APPARATUS

George H. Strickland, Oakwood, Ohio, assignor to
 General Motors Corporation, Dayton, Ohio, a
 corporation of Delaware

Application September 25, 1940, Serial No. 358,332

5 Claims. (Cl. 62—108.5)

My invention relates to ice trays and grids of the type employed in household mechanical refrigerators for the making of small blocks of ice; and particularly to that type wherein the ice blocks are mechanically released from the grid and from the trays by relative movement of the grid walls.

In ice trays of this type, it has been the custom heretofore to divide the interior of the tray into a plurality of small compartments by extending the relatively movable grid or dividing walls from the top to the bottom of the tray. In this manner the water has been frozen into separate or individual ice blocks, each separated from the others by grid walls and each removable from its compartment by relative movement of the grid walls.

To improve upon such prior ice trays and grids and upon the method of removing ice in block form therefrom, is the principal object of my invention. I accomplish this principal object by employing a principle sometimes used in the harvesting of ice on a commercial scale; that is, the principle involving first scoring or marking the surface of the body of ice into sections of the size desired and then by the application of force causing said body of ice to split throughout its depth along the markings or scorings to form smaller blocks of ice.

In employing this principle to accomplish the principal object of my invention, I provide an improved tray including a grid structure having relatively movable walls and designed to fit only into the upper portion of the tray, leaving the lower portion of the tray unobstructed by the grid walls. Thus, in my improved grid, the movable grid walls perform two functions; first, they serve to score or mark the upper surface of the body of ice formed in the tray and secondly, when moved relative to one another by the application of force, they serve to split the large body of ice throughout its depth into smaller blocks of the size desired.

Incident to the main object of my invention which is set forth above, numerous other more specific objects will become apparent from the following description and claims, reference being had to the accompanying drawings wherein:

Fig. 1 is a top plan view of a freezing device constructed in accordance with the present invention including a tray and a grid structure disposed in the tray;

Fig. 2 is a sectional view of the device taken on the line 2—2 of Fig. 1 with the grid structure shown in elevation;

Fig. 3 is a transverse sectional view of the de-

vice taken on the line 3—3 showing the transverse walls of the grid interlocked with the longitudinal walls thereof;

Fig. 4 is a view similar to Fig. 2 illustrating ice frozen in the device and showing one of the transverse grid walls moved to break ice blocks from the body of ice;

Fig. 5 is a transverse sectional view of the device taken on the line 5—5 of Fig. 4;

Fig. 6 is a view of the freezing device illustrating the grid elevated relative to the tray and showing ice blocks in the tray that have been released from the grid; and

Fig. 7 is a view similar to Fig. 2 showing a modified form of grid structure disposed in a tray for carrying out the present invention.

Referring to the drawings, for illustrating my invention, I have shown in Fig. 1 thereof, a freezing tray of the type used in household refrigerators. The freezing device comprises a pan or tray 10 having side walls 11, end walls 12 and a bottom wall 14. The side walls 11 of the tray 10 are diverged outwardly toward the top of the tray (see Fig. 3) and the end walls 12 thereof are also diverged outwardly toward the top of tray 10 at a greater angle than the side walls (see Fig. 2) to facilitate removal of ice from the tray. The upper edge of the side and end walls 11 and 12 respectively of the tray 10, are bent or rolled over to form a rim 16 around the top thereof which rim stiffens the tray against deformation. Opposed end walls 12 of tray 10 are provided centrally thereof with a vertically disposed outwardly depressed portion 17 (see Fig. 2) which extends from the rim 16 downwardly to a point approximately midway between the top and bottom of the tray. The depressed portions 17 in the tray end walls 12, form grooves 18 (see Fig. 1) which grooves are adapted to receive a portion of a grid 20 to be disposed in the tray in the manner and for the purpose to be hereinafter described. The tray 10 may, if desired, be covered with any suitable wax coating to facilitate the release of ice therefrom.

Within tray 10, I place a unitary removable metallic grid structure 20 comprising a rigid or substantially inflexible longitudinal wall 21 and a plurality of rigid or substantially inflexible transverse walls 22. The metal walls of grid 20 may also, if desired, be covered with any suitable wax coating to facilitate the release of ice therefrom. The transverse walls are arranged in spaced apart relationship along the length of the longitudinal wall 21 and are loosely mounted in upper and lower slots 23 and 24 respectively, provided in

wall 21. For example, walls 22 may be provided with an opening 26 which is slit as at 27 (see Fig. 3), to permit the walls 22 to be assembled over web portions 28 intermediate the slots 23 and 24 of longitudinal wall 21. The openings 26 are preferably of sufficient length to pass freely over the widest portion of the webs 28 of wall 21 so as to permit movement of the walls 22 in a manner and for the purpose presently to be described. Each upper slot 23 in wall 21 has an inclined bottom wall 29 and the slots 23 and 24 together with wall 29 of slots 23 are constructed and arranged to maintain the transverse grid walls 22 normally in an inclined position with respect to the vertical. The slots 23 and 24 permit transverse walls 22 to be moved toward the vertical relative to the longitudinal wall 21 and this movement is preferably first a tilting and then a sliding movement in a direction lengthwise of wall 21.

In order to prevent tilting of the entire grid structure 20 relative to tray 10 when the grid is initially placed therein, I hold the grid in the same horizontal plane with tray 10 by disposing ends 31 of longitudinal grid wall 21 in the grooves 18 at opposed ends of the tray.

While I have shown grooves in opposed end walls of the tray for the reception of end portions of a grid, it is to be understood that any means may receive the grid to hold same in the upper part of the tray and in horizontal alignment therewith. For example, all edges of the grid walls may be shaped to fit against the diverging tray walls to support the grid within the tray since the grid walls are adapted to be moved from an inclined position toward the vertical.

It will be noted that the grid walls 21 and 22 extend only to a point about midway between the top of tray 10 and its bottom wall 14. Thus the interior of the tray is divided into two sections or portions, one an upper portion that is partitioned by the grid walls 21 and 22, and the other a lower portion which is unobstructed by the grid walls. When liquid is frozen into a body of ice in the freezing device the walls 21 and 22 of grid 20 form relatively deep surface markings or scorings in the ice.

In operation, movement of the grid walls relative to one another causes the block of ice to split from top to bottom thereof on lines substantially parallel to and in alignment with the scorings formed by the grid walls.

Referring now to Fig. 4, wherein I have shown a liquid frozen into a body of ice within tray 10 and have illustrated the walls 21 and 22 of grid 20 frozen in the body of ice 36, to provide a plurality of scorings therein as indicated at 37, I disclose the one end transverse grid wall 22 as having been tilted or moved relative to the longitudinal grid wall 21 by a lever or prying tool 38. While any suitable prying tool may be employed for moving the transverse grid walls, I prefer the use of a lever of the type disclosed in the James W. Jacobs copending application Serial No. 340,293, filed June 13, 1940. Tilting movement of the end transverse grid wall 22 as disclosed in Fig. 4 of the drawings, causes the ice to split, as at 39, below scoring 37. The ice also splits below the scoring 37 formed therein below the longitudinal grid wall 21 on a line as indicated at 41, in Fig. 5 of the drawings. This movement of the wall 22 relative to wall 21 breaks a pair of ice blocks 42 at the end of tray 10 from the body 36 thereof in the tray. Continued movement of the grid transverse wall 22 will cause same to slide lengthwise of wall 21 and this further movement

thereof forces the ice blocks 42 upwardly upon the tray end wall 12 to release the ice blocks 42 entirely from walls of the grid 20.

The angle of inclination of the end wall 12 of tray 10 may be varied somewhat in accordance with that part of the functioning thereof when the end ice blocks 42 are forced thereagainst. For example, end wall 12 may, if desired, be of such angle with respect to the vertical, as to cause the entire body of ice 36 to be broken away from walls of the tray and slightly elevated when the end ice blocks 42 are forced against the one end wall 12 of the tray. However, this breaking of the entire body of ice 36 from the tray is not necessary since in the present disclosure the transverse grid walls 22 are adapted to be moved relative to the longitudinal grid wall 21 by separate and successive independent operations of the tool or lever 38 to break ice blocks from the body of ice in sequence from one end to the opposite end of the device.

In Fig. 6 of the drawings, I have shown the grid 20 removed from tray 10 after having completed the independent operations of lever 38 as described to produce a plurality of ice blocks which are positioned in the tray and which blocks may be readily removed from the tray when their use is desired. It will be noted that after the grid walls 22 have been moved to produce or break ice blocks from the body of ice 36, and the lever 38 has been released from the cross walls 22, these walls will slide down the inclined bottom wall 29 of the upper slots 23, provided in longitudinal grid wall 21, thereby to reassume their normal inclined position relative to the vertical. The walls 22 of grid 20 are all therefore in their proper position to provide the inclined scores or scorings 37 when the grid is replaced in a tray containing a liquid to be frozen.

Since the principle of my invention and the method of scoring the body of ice together with the breaking of the ice along the scorings to produce a plurality of ice blocks is not restricted to the particular grid structure hereinbefore described, I show in Fig. 7 of the drawings, one other of many forms of grid structures that may be employed to carry out the objects of my invention. The grid 40 disclosed in Fig. 7 is preferably of the same general character and design as the grid structure fully illustrated and described in the copending application of Donald H. Reeves, Serial No. 98,213, filed August 27, 1936. It should be understood from the foregoing that the lower portion of the longitudinal wall 41 and transverse walls 42 of the grid 40 are omitted or that the use of only substantially half of the height of these walls is essential in the present invention.

In the operation of grid 40, a lever 43 is raised to cause its cam end 44 to engage and exert a force against the top of the tray 10 and this force elevates the entire body of ice relative to the tray. Continued upward movement of lever 43 moves, through suitable linkage mechanism, an operating bar or member 46 lengthwise of the longitudinal wall 21. This lengthwise movement of bar 46 causes same to engage and move the transverse walls 42 progressively from one end to the other end of the grid structure 40 relative to the longitudinal wall 41 thereby sequentially to break ice blocks, along scorings made in the body of ice by walls 41 and 42, from the body of ice and to release these blocks from the grid walls. A more detailed description of the construction and method of operating the transverse walls 42

of grid 40, may be had by reference to the co-pending application of Donald H. Reeves, above identified, and no further explanation thereof is necessary herein.

From the foregoing, it will be apparent that I have provided an improved freezing device and a novel method of producing and harvesting ice blocks therefrom. By my improvement, the cost of grid structures for disposition in ice trays is greatly reduced, and the amount of ice produced in the tray is increased due to the fact that material employed in the construction thereof has been reduced to a minimum or substantially only half that formerly required in the manufacture of such grids. Other advantages are also obtained by my invention over former devices. For example, scratching and marring of walls of the tray and particularly the bottom wall thereof, usually caused by movement of the grid walls relative to one another while contacting the tray bottom, is eliminated since the walls in the present grid are definitely pivoted within the body of ice and without engagement with the tray bottom. This is an important advantage since most of the trays now on the market are provided with a wax coating and pivoting or movement of grid walls in contact with the tray bottom scratches or breaks through this coating to destroy its continuous character which results in stronger adhesion of the ice to the metal of the tray.

My improved device and the method of operating same result in the production of ice blocks which are substantially of the same size and configuration as produced by former devices wherein the grid walls extend to the bottom of the tray, and these ice blocks are produced without undue breaking or chipping of parts thereof therefrom.

While the form of embodiment of the invention as herein disclosed, constitutes a preferred form, it is to be understood that other forms might be adopted, all coming within the scope of the claims which follow.

What is claimed is as follows:

1. In combination, a tray adapted to contain a body of water to be frozen into an ice block substantially of the size of the tray, means associated with the tray for breaking up the body of ice into a plurality of small ice blocks, said means comprising a grid of substantially less height than the height of the tray and including a longitudinal wall having a plurality of transverse walls mounted for movement relative thereto, means for spacing said grid from the bottom of the tray with the walls thereof depending into the upper portion of the body of ice when formed, whereby the upper surface and portion of said body of ice formed in the tray is scored or marked off into sections of the desired shape, and means for causing relative movement of said walls whereby to split the frozen body throughout its depth and along said scorings to provide small ice blocks.

2. In combination, a tray adapted to contain a body of water to be frozen into an ice block substantially of the size of the tray, means associated with the tray for breaking up the body of ice into a plurality of small ice blocks, said means comprising a grid of substantially less height than the height of the tray and including a longitudinal wall having a plurality of trans-

verse walls mounted for movement relative thereto, means for spacing said grid from the bottom of the tray with the walls thereof depending into the upper portion of the body of ice when formed, whereby the upper surface and portion of said body of ice formed in the tray is scored or marked off into sections of the desired shape, and means attached to said grid and operable to cause relative movement between the walls thereof whereby to split the frozen body throughout its depth and along said scorings to provide small ice blocks.

3. In combination, a tray adapted to contain a body of liquid to be frozen, means removably disposed in said tray, said means comprising a grid of substantially less height than the height of the tray, said grid comprising a longitudinal wall and a plurality of walls extending transversely thereof and mounted for movement relative thereto, means for spacing said grid a substantial distance from the bottom of said tray whereby the grid divides the interior of the tray into an upper partitioned portion and a lower unobstructed portion, said grid walls normally depending into the upper portion of the body of liquid in the tray to provide a plurality of scorings in the body when the liquid is frozen, and means for moving said transverse grid walls relative to said longitudinal grid wall to break the frozen body along said scorings into a plurality of blocks.

4. In combination, a tray adapted to contain a body of liquid to be frozen, means removably disposed in said tray, said means comprising a grid of substantially less height than the height of the tray, said grid comprising a substantially inflexible longitudinal wall and a plurality of substantially inflexible walls extending transversely thereof and mounted for movement relative thereto, said tray having a vertically disposed depression in the upper part of opposed ends thereof, the ends of said longitudinal grid wall fitting within said depressions for supporting said grid a substantial distance from the bottom of said tray whereby the grid divides the interior of the tray into an upper partitioned portion and a lower unobstructed portion, said grid walls normally depending into the upper portion of the body of liquid in the tray to provide a plurality of scorings in the body when the liquid is frozen, and means for moving said transverse grid walls relative to said longitudinal grid wall to break the frozen body along said scorings into a plurality of blocks.

5. The method of making ice and of harvesting the ice in small block form from an ice tray of the type generally employed in household mechanical refrigerators which consists in, freezing a body of water in the tray and, during the freezing operation, scoring or marking the upper portion and surface of the ice into a plurality of sections of the desired shape, whereby the body of water is frozen into a solid block of ice having scorings or markings in its upper portion, and applying force to the means used for scoring or marking the block of ice to move the means horizontally whereby said block of ice is split throughout its depth along the scorings or markings.

GEORGE H. STRICKLAND.
